UNITED STATES PATENT OFFICE.

ARTHUR W. BROWNE, OF NEW YORK, N. Y., ASSIGNOR TO THE S. S. WHITE DENTAL MANUFACTURING COMPANY, OF PHILADELPHIA, PENNSYLVANIA.

DESIGN FOR A FOUNTAIN SPITTOON-BOWL.

SPECIFICATION forming part of Design No. 30,744, dated May 9, 1899.

Application filed October 17, 1898. Serial No. 693,835. Term of patent 14 years.

To all whom it may concern:

Be it known that I, ARTHUR W. BROWNE, a citizen of the United States, residing at New York, (Prince's Bay,) in the county of Richmond and State of New York, have invented a certain new and useful Design for Fountain Spittoon-Bowls; and I do hereby declare the following to be a full, clear, and exact description of the invention, such as will enable others skilled in the art to which it appertains to make and use the same.

The leading feature of my design consists of a dental fountain spittoon-bowl which from top to bottom is circular in horizontal section, and in vertical section consists of the outwardly-curved side, the flat and almost horizontal bottom having a downward pitch toward the center of the bowl of approximately three and one-half degrees ($3\frac{1}{2}$) from the horizontal, the central portion of the bowl being curved downwardly and inwardly and extended to form a central cylindrical opening or neck, the downwardly and inwardly curved portion of the bowl forming a quadrant of a circle, the diameter of which is approximately equal to that of the central cylindrical opening or neck.

The design is illustrated in the accompanying drawings, in which—

Figure 1 is a top or plan view showing the horizontal circular outline of the bowl, and

Fig. 2 is a vertical central section through the bowl.

I will now more particularly describe my design as follows: The entire bowl is circular 35 in horizontal section from the top of its rim A^2 to the lower extremity of its central opening or neck A' . In its vertical section the bowl is curved outwardly to form the side A^3 , which extends from about a to a' continuously 40 around the bowl. The side of the bowl merges into the substantially flat bottom A^4 , which extends from a' to about a^2 and which has a downward pitch toward the center of the bowl of approximately three and one-half degrees 45 ($3\frac{1}{2}$) from the horizontal. Commencing approximately at a^2 the bowl curves downwardly and inwardly at A^5 until at a^3 it merges into the central cylindrical opening or neck A' . The curve A^5 , extending from a^2 to a^3 , forms 50 a quadrant of a circle the diameter of which is approximately equal to the diameter of the central cylindrical opening or neck A' .

I claim as my invention—

The design for a dental fountain spittoon-bowl, substantially as shown and described.

In testimony whereof I affix my signature in presence of two witnesses.

ARTHUR W. BROWNE.
